CARBOY CONTAINER

Oscar Fisher, Locust Valley, N. Y.

Application November 7, 1942, Serial No. 464,924

8 Claims. (Cl. 217—52)

This invention relates to carboy containers and particularly to an improved form of box for receiving a large bottle and protecting it against breakage by shock or impact during transportation, storage and use.

Boxes of the types heretofore used in carboys have been constructed and arranged to include cushioning means bearing against and supporting the bottles in spaced relation to the sides, top and bottom of the box. The cushioning means have taken many different forms, such as resilient slats, cork pads, and the like, which are used to absorb shock and reduce the tendency of the bottle to break when the carboy is dropped or subjected to impact.

All of these prior boxes have one characteristic in common, namely, that the cushioning means engage the bottles at spaced apart lines or spots. With this type of cushioning means, any shocks caused by dropping or subjecting the carboy to impact are concentrated at a few widely spaced spots or lines, with the result that the forces at these points may be sufficiently great to break the bottle.

An object of the present invention is to provide a receptacle for a bottle which distributes shocks over a wide area at the zones of greater strength of the bottle and thereby reduces the forces to which any zone or part of the bottle is subjected.

Another object of the invention is to provide carboy boxes that support the bottles resiliently over a wide surface area and thus, by distributing shock or impact, prevent breakage of the bottles.

A further object of the invention is to provide carboy boxes that support the bottles resiliently to decelerate movement of the bottles under shock or impact and prevent concentration of the forces set up by shock, impact or the inertia of the bottle.

An additional object of the invention is to provide carboy boxes that are capable of flexing to absorb shock or impact and thereby reduce the forces acting directly on the bottle.

Other objects of the present invention will become apparent from the following description of a typical embodiment of the invention.

In accordance with the present invention, I have provided a box formed of any suitable type of material such as, for example, wood, plywood, plastics, metal or any desired combination of the same, in which the top and bottom are provided with a plurality of arcuate members adapted to engage and receive the top and the bottom of a bottle throughout substantially its entire circumference. The top, bottom and side panels of the box preferably are somewhat resilient so that

they can flex slightly under impact to absorb shock.

More particularly, the arcuate members which support the bottle may be formed of resilient material, such as wood, and are arranged to form, in effect, cantilever constructions secured to the bottom and top of the box which are capable of giving under shock or impact. These members are sufficiently resistant to distortion to prevent the bottle from coming in contact with the walls of the box. Moreover, their relationship to the remainder of the box is such that they form a resilient suspension for the bottle in which the side, top and bottom panels of the box act as springs to cushion the relative movements of the box and the bottle. The arcuate members are of such width that the forces exerted on the box and the bottle by shock or impact are distributed over relatively wide zones at the top and bottom of the bottle where the bottle is strongest and thereby prevent a concentration of forces in small areas or spots at the weaker portions of the bottle.

For a better understanding of the present invention, reference may be had to the accompanying drawings in which:

Figure 1 is a top plan view of a typical form of carboy box embodying the present invention, with the cover removed;

Figure 2 is a bottom plan view of the cover for the box;

Figure 3 is a view in cross-section taken on line 3—3 of Figure 1; and

Figure 4 is a view in cross-section taken on line 4—4 of Figure 3 through a corner of the box.

The form of carboy box chosen for purposes of illustration includes four corner rails 10 formed of square stock having chamfered inner and outer edges and in which are mortised the four side panels 11 of the box. The upper edges of the panels 11 and the upper ends of the corner rails 10 are secured to top rails 13 which have their ends mitered and secured together in any suitable way such as, for example, by means of glued dowels 14. The upper edges of the panels 11 may be received in mortises in the top rails 13. The top rails 13 are provided with inner rabbeted edges 13a within which the top 15 is received. The top rails 13 and corner rails 10 project outwardly beyond the side panels 11 and thereby tend to shield the panels 11 from direct impact. Inasmuch as these panels 11 are protected to a certain extent, they can be formed of thinner and more resilient material which acts as a cushioning means, as will be explained presently.

As illustrated in Figures 2 and 3, the top may

consist of a generally square panel 16 fitting snugly within the open top of the box and resting in the rabbeted edges 13a of the top rails 13. The panel 16 is provided with a central hole 17 for receiving the neck of a bottle B, as shown particularly in Figure 3.

Projecting downwardly from the panel 16 are a plurality of arcuate members 18 forming a substantially annular flange for receiving the upper portion of the bottle. The ends of the arcuate members 18 are spaced apart in order to permit them to give slightly under impact caused, for example, by dropping of the carboy.

Each of the arcuate members 18 is secured to the top panel 16 by means of an outer corner block 19 having a concave inner face 19a abutting the outer surface of the arcuate member and being secured as by gluing to the inner surface of the panel 16. The outer edges 19b of the block 19 abut the inner edges of the rails 13 when the corner is applied. A second block 20 having a convex outer face 20a and an inclined inner face 20b is secured to the undersurface of the panel and to the inner surface of the arcuate member 18. Each of the blocks 19 and 20 is of less height than the arcuate member 18 so that a substantial portion of the arcuate member is unsupported and, therefore, can flex slightly.

The top described above may be detachably secured to the box by means of screws or other fastenings extending through the top rails 13 into the corner blocks 19.

The bottom of the box may be formed of a square panel 21 which is mortised into the corner rails 10 and secured thereto and to the side panels by means of strips 22 disposed within the panels 11 (Fig. 3). If desired, the bottom of the box may be provided with skid rails 23 on two opposite sides thereof for taking the wear on the box caused by sliding it along the floor or the like.

Supported on the bottom panel 21 are a series of four arcuate members 24 arranged similarly to the arcuate members 18 on the top of the box. The members 24 are secured to the panel 21 by means of corner blocks 25 secured to the bottom panel 21. Each of the blocks 25 is provided with a concave inner face 25a fitting the arcuate member 24 snugly and being secured thereto by glue or in any other suitable way. The outer surface 25b of the block 25 abuts against the side panels 11 and the corner rails 10 so that outward shifting movement of the arcuate members 24 is prevented. Within the arcuate members 24 and supported in spaced relationship to the bottom panel 21 is a disc-like panel 26 which is supported at its edges only and therefore has limited resiliency. The panel 26 may be supported by a plurality of arcuate elements 27 (Figs. 3 and 4) which are secured in abutting relationship to the elements 24 and to the bottom panel 21 of the container. As illustrated in Figure 4, the arcuate members 27 may be of less length than the arcuate members 24.

The arcuate supporting members 24 have free edges projecting upwardly to receive the bottom zone of the bottle B. Inasmuch as the members 24 are supported at their lower end portions only, they are capable of flexing slightly to cushion the bottle B against impact.

The box may be further reinforced by means of bottom rails 28 extending along the lower edges of the panels 11 and secured in any suitable way to the corner rails 10. The rails 29 may be secured to the corner rails 10 to serve as handles for moving the carboy.

The construction described above has the advantage that the bottle B, as illustrated in Figure 3, is supported throughout substantially its entire circumference and throughout a relatively wide zone at the top and bottom where the bottle is inherently the strongest. With this arrangement, even when the filled bottle weighs one hundred or more pounds, as is often the case, any impact on the box will be distributed over such a wide area of the bottle at zones that are best suited to resist breakage that no part of the bottle is subjected to forces sufficient to cause breakage of the bottle.

In addition to the cushioning effect of the arcuate flanges 18 and 24, the side and end panels 15 of the box, also, absorb shocks by their inherent resiliency. For example, when the carboy is dropped on its side, the bottle B tends to shift to the under side. As a result, the arcuate members 18 and 24, in the direction of movement of the bottle, are flexed outwardly. Because of the cantilever arrangement of the members 18 and 24, they tend to flex the top and bottom panels of the box. Inasmuch as these panels are connected to the side panels 11 and the corner, bottom and top rails 10, 21 and 13, these elements and the side panels 11 bulge slightly, thereby acting as springs to absorb the shock and resist the shifting movement of the bottle.

Similarly, if the carboy is dropped on its bottom, the bottom panel 21 and the supporting panel 26 bulge downwardly, causing the arcuate member 24 to grip the bottle B more tightly and causing bowing of the side panels 11.

The deceleration of the movement of the bottle 35 resulting from the shock absorbing action of the box is sufficient to protect the bottle even under conditions of shock far in excess of those normally encountered in the handling of such carboys. In addition, the arrangement of the supporting 40 members for the bottle is such that forces in substantially any direction will be resisted resiliently by the supporting elements and the bottle cannot be thrown against the sides of the box and thus broken by direct impact with the box.

From the foregoing description of a typical form of box embodying the present invention, it will be apparent that I have provided a simple, yet highly effective, type of carboy box which is capable of affording maximum protection to the bottle therein.

It will be understood that my carboy box is susceptible to considerable modification in structural details, for example, in the shape and size of the box, the manner in which the outer panels and corners of the boxes are constructed and in the manner in which the arcuate supporting members therein are secured to and supported within the box. Therefore, the embodiment of the invention chosen for purposes of illustration should be considered as illustrative, only, and not as limiting the scope of the following claims.

I claim:

1. An individual carboy container comprising a box having resilient sides, a resilient bottom and a removable top, a plurality of spaced arcuate members having lower portions secured to the bottom of said box and having free upper edges, said spaced arcuate members defining the circumference of a circle having its center substantially at the center of the bottom of the box and being adapted to receive and engage the sides of a bottle of circular cross-section throughout a zone of substantial width, a plurality of spaced arcuate members having upper edges secured to said top and free lower ends projecting downwardly into

said box, said spaced arcuate members defining the circumference of a circle having its center substantially at the center of the top of the box and being adapted to receive and engage said bottle throughout a zone of substantial width.

2. In a carboy container, the sub-combination of a bottom for the container, a plurality of arcuate members secured to said bottom in a ring to receive and engage the sides of a bottle, a circular panel within said arcuate members and in spaced relation to said bottom for supporting said bottle, and means supporting said panel at its edges to permit said panel to flex under impact.

3. In a carboy container, the sub-combination of an end panel for the container, a plurality of arcuate members secured to said panel in a ring and forming the major portion of the circumference of the ring, and means of less height than said arcuate members engaging the inner and outer surfaces of said members for securing said members to said panel, the remaining portion of said members being free and engageable resiliently with the sides of a bottle.

4. In a carboy container, the sub-combination of an end panel for the container, a plurality of spaced arcuate resilient members on said panel arranged in a ring to receive and engage the sides of a bottle, means of less height than said resilient members secured to said panel and engaging the inner and outer surfaces of said members to rigidify the portions of said members adjacent said panel and leave the outer portions of said members unsupported and free to engage resiliently the sides of a bottle, and means within said ring for supporting said bottle resiliently in spaced relation to said end panel.

5. In a carboy container, the sub-combination of an end panel for the container, a plurality of spaced arcuate resilient members on said panel arranged in a ring to receive and engage the sides of a bottle, means of less height than said resilient members secured to said panel and engaging the inner and outer surfaces of said members to rigidify the portions of said members adjacent said panel and leave the outer portions of said members unsupported and free to engage resiliently the sides of a bottle, and a resilient panel within said arcuate members for supporting said bottle, said resilient panel being supported at its

edges in spaced relation to said end panel by the means engaging the inner surfaces of said members.

6. A carboy container having a bottom, sides and a removable top, said sides comprising panels, mortised corner rails for receiving the lateral edges of said panels, top rails secured to the upper edges of said panels and said corner rails, recesses in the inner edges of said top rails forming shoulders for receiving said top, bottom rails secured to the lower edges of said panels and said corner rails, said bottom comprising a panel disposed within said side panels and mortised into said corner rails, and means on said top and said bottom panel for engaging the periphery of a bottle at spaced apart zones of substantial width extending around the major portion of the periphery of said bottle.

7. A carboy container comprising a box having resilient ends and sides, a plurality of spaced cantilever members secured to each end of said box with their free ends extending inwardly and engageable with the circumference of a cylindrical bottle, adjacent the opposite ends thereof, and means for resiliently supporting the bottom of the bottle in raised position with respect to the bottom of said box, said raised means cooperating with said cantilever means in supporting said bottle in spaced relationship to the ends and sides of said box and in transmitting thrusts due to movements of said bottle to the ends and sides of said box to cause them yieldingly to resist said relative movements.

8. A carboy container comprising a box having relatively rigid top, bottom and corner rails, resilient panels secured to said rails forming the top, bottom and sides of said box, spaced cantilever means in said box supported on the top and bottom panels respectively in spaced apart relationship for engaging spaced apart areas of the surface of said bottle and thereby maintaining said bottle in spaced relation to said corner rails and the sides of said box, said means resisting relative movement of said bottle and said box and transmitting relative movement of said box and bottle under impact to said side, top and bottom panels to cause them to flex and absorb at least a portion of said impact.

OSCAR FISHER.
